US00D978660S

(12) **United States Design Patent** (10) **Patent No.:** **US D978,660 S**
(45) **Date of Patent:** **** Feb. 21, 2023**

(54) **BUMPER**

(71) Applicant: **ShenZhen YiHong Technology Co., LTD**, Guangdong (CN)

(72) Inventor: **Yi Dai**, ShenZhen (CN)

(73) Assignee: **ShenZhen YiHong Technology CO., LTD**, ShenZhen (CN)

(**) Term: **15 Years**

(21) Appl. No.: **29/819,976**

(22) Filed: **Dec. 18, 2021**

(51) LOC (14) Cl. **08-09**

(52) U.S. Cl.

USPC **D8/402**

(58) **Field of Classification Search**

USPC D8/1, 353, 354, 366, 402, 403; D3/304, D3/273, 201; D9/424, 504

CPC B65D 21/0233; B65D 21/0235; B65D 21/0234; B65D 21/00; B65D 21/02; B65D 2519/00955

(57) **CLAIM**

The ornamental design for a bumper, as shown and described.

DESCRIPTION

FIG. 1 is a perspective view from above of a bumper, situated along an edge, showing my new design;

FIG. 2 is a perspective bottom view thereof;

FIG. 3 is a front view thereof;

FIG. 4 is a back view thereof;

FIG. 5 is a left side view thereof;

FIG. 6 is a right side view thereof;

FIG. 7 is a top view thereof;

FIG. 8 is a bottom view thereof;

FIG. 9 is a perspective view of the bumper shown in a use environment of a container;

FIG. 10 is a perspective view of the bumper shown in a use environment of containers in a stacked configuration; and

FIG. 11 is a perspective view from below thereof.

FIG. 12 is a perspective view from above of a plurality of bumpers organized around corner regions of a plurality of containers;

FIG. 13 is a perspective view from below thereof;

FIG. 14 is a perspective view of a second embodiment of a bumper with a degree of transparency; and,

FIG. 15 is a perspective view of a plurality of transparent bumpers organized around corner regions of a container.
